US00D960989S

(12) **United States Design Patent** (10) **Patent No.:** **US D960,989 S**
Dai (45) **Date of Patent:** **** Aug. 16, 2022**

(54) **BLUETOOTH EARPHONE**

(71) Applicant: **SHENZHENSII ANNSO TECHNOLOGY CO., LTD**, Shenzhen (CN)

(72) Inventor: **Chunlai Dai**, Shenzhen (CN)

(**) Term: **15 Years**

(21) Appl. No.: **29/782,778**

(22) Filed: **May 10, 2021**

(30) **Foreign Application Priority Data**

Mar. 12, 2021 (CN) 202130134728.4

(51) **LOC (13) Cl.** **21-01**

(52) **U.S. Cl.**

USPC **D21/333**

(58) **Field of Classification Search**

USPC D21/333; D14/205, 206, 207, 217, 221, D14/223, 224, 225; D24/173, 174

CPC .. H04R 1/1016; H04R 1/1058; H04R 1/1091; H04R 1/10; H04R 1/1066

See application file for complete search history.

Primary Examiner — Mehri F Bajoul

(57) **CLAIM**

The ornamental design for an Bluetooth earphone, as shown and described.

DESCRIPTION

FIG. 1 is a perspective view of a Bluetooth earphone showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the Bluetooth earphone that form no part of the claimed design.

1 Claim, 8 Drawing Sheets
